UNITED STATES PATENT OFFICE

FRANK PARDEE, OF HAZLETON, PENNSYLVANIA, ASSIGNOR TO ANTHRACITE SEPARATOR COMPANY, OF HAZLETON, PENNSYLVANIA, A CORPORATION OF PENNSYLVANIA

FLEXIBLE LOWERING APPARATUS

Application filed July 9, 1932. Serial No. 621,602.

This invention relates to improvements in apparatus for lowering coal or like lump material with a minimum amount of breakage. The invention further aims to provide a compact collapsible apparatus which can be inexpensively manufactured and yet perform its intended function equally as well as more complex expensive lowering apparatus heretofore available.

10. The invention will be fully apparent from the following specification when read in connection with the accompanying drawings and will be defined with particularity in the appended claims.

15. In the drawings—

Fig. 1 is a view in longitudinal vertical section illustrating one embodiment of the invention;

20. Fig. 2 is an elevation from the left end of Fig. 1, the lower part of the apparatus being broken away;

25. Fig. 3 is a view similar to Fig. 1, but showing the collapsed starting position of the flexible chute;

Fig. 4 is a detail top view of the flexible chute;

30. Fig. 5 is an enlarged vertical section of the lower portion of the chute;

Fig. 6 is a fragmentary plan of the parts shown in Fig. 5.

Referring in detail to the drawings, 10 represents a bin or like receptacle for the storage of coal or other lump material. Extending outwardly from this bin, there is a chute 12. This chute is adapted to discharge coal from the bin onto my improved flexible lowering chute, indicated as a whole at 14. My improved lowering chute is of tubular form, preferably, though not necessarily, round in plan and is formed of flexible mesh or chain-like fabric, such as indicated at 16. This chain mesh collapsible tube or chute, at its upper end, is secured to a ring 17 which may be conveniently formed of angle iron. This ring is suspended by a plurality of rods

18 from an overhead support such as an outwardly extending beam 20 secured to the supporting structure for the bin or any other convenient fixed structure.

At spaced intervals along the length of the collapsible chute or tube 14, I preferably secure hoops 22 by means of rings 23 secured to the fabric. These hoops carry guide eyes 24 for cables or other flexible members 26. These members 26 at their lower ends are secured to a funnel-like discharge shell 28. This shell includes an upper substantially cylindrical portion 30 and a lower inwardly tapering or funnel-like portion 32, the lower end of which is provided with a restricted outlet 34.

The several cables 26 are adapted to jointly support the discharge shell in various positions of vertical adjustment. These cables pass over guide sheaves 36 carried by the rings 16 and also over other sheaves 38 and are fastened to a ring or shackle 40 which in turn is connected to a cable 42 adapted to be wound on a winch or drum 44 driven by a suitable motor 46, whose circuit and direction of rotation is controlled by a suitable controller 48.

For controlling the outflow of material at the lower end of the flexible discharge shell, I provide an adjustable closure member which is adapted to coact with the outlet opening 34 formed in the lower part of the discharge shell. In the embodiment of the invention illustrated, this closure member is in the form of a ball 50 suspended from a cable 52 which passes over guide sheaves 54 and 56. One extremity of the cable 52 is secured to a drum 58 which is adapted to be either manually or power-operated so as to control the discharge of material from the lower end of the chute 14.

In the normal operation of the apparatus, when no coal is flowing, the flexible chute 14 will be collapsed, as indicated in Fig. 3. This is accomplished of course by operating the motor 46 so as to wind the cable 42 on the

drum 44. At the same time, the drum 58 will be turned to a position to bring the closure member 50 into tight engagement with the discharge opening 34 in the shell 32. With parts in the position of Fig. 3, the outlet gate 60 for the storage bin 10 will be opened and as the coal or other lump material fills up the flexible mesh chute 14 the same will gradually be lowered, the rate of lowering being determined by the rate at which the coal flows from the storage bin 10, this being desirable so that the coal will not fall any great distance, thus preventing undue breakage. The drum 44 will be caused to turn slowly until the lower end of the discharge shell 32 reaches a point immediately above the bottom of the coal car, barge, or other carrier, into which the material is to be discharged. Then the drum 58 will be operated in the proper direction so as to permit the weight of the coal in the chute to unseat the closure 50, thereupon the coal will slowly flow from the opening 34 in the discharge shell 32.

As the coal flows downwardly, the pile will gradually build up in the car or vessel. As the pile builds up, the flexible chute will be gradually elevated by causing cable 42 to be wound up on the drum 44. In this way it will be understood that the coal can be effectively lowered with a minimum amount of breakage.

As the cables 26 are pulled up, the successive sections of the chain mesh fabric located between adjacent encircling hoops 22 secured thereto will fold inwardly and neatly nest against the tapered or funnel-like portion 32 of the discharge shell, as indicated graphically in Figs. 3 and 5.

The flexible mesh fabric is formed of a multiplicity of chain-like links. Such link fabric is producible on wire-work machines and can be economically manufactured. This enables me to produce a relatively inexpensive collapsible lowering chute which nevertheless functions very effectively and provides a structure which can be readily accommodated in a very small and compact space when collapsed. The great flexibility of chain mesh fabric is important in apparatus of this character because it has little tendency to stick or bind as is the case with nested tubes and the like. These and other advantages of the described construction will be readily apparent to those skilled in the art.

While the flexible tube-like element illustrated is substantially circular in plan it is of course apparent that tubes of other shapes such as elliptical, polygonal or other shapes in plan can be just as readily employed. Where the term "tube like element" is used herein it is intended to apply to any flexible hollow collapsible element without limitation as to the particular shape, it being apparent that the effective shape of the tube can be

varied by varying the contour in plan to which the hoops 22 are fashioned.

Various modifications and substitution of equivalents may be made by those skilled in the art without departure from the invention as defined in the appended claims.

What I claim is:—

1. Lowering apparatus comprising a flexible fabric element adapted to confine a mass of coal or like lump material flowing from a higher to a lower elevation, means supporting the upper end of said fabric element, means for successively collapsing separate sections of the fabric element and means for controlling the outflow of material from the lower end thereof. 75 80

2. Lowering apparatus comprising a hollow element of flexible fabric, a shell-like member adapted to accommodate the latter when collapsed, means for raising and lowering said member and means controlling the outflow of material from said member. 85

3. Lowering apparatus comprising a tube-like element of flexible mesh fabric adapted to receive material at the top and discharge it at the bottom, a discharge shell at the bottom of said element adapted to accommodate the fabric when the element is collapsed and flexible suspension members supporting said shell. 90 95

4. Lowering apparatus comprising a tube-like element of flexible mesh fabric adapted to receive material at the top and discharge it at the bottom, a discharge shell at the bottom of said element adapted to accommodate the fabric when the element is collapsed and flexible suspension members supporting said shell and means controlling the discharge of material from said shell. 100

5. Lowering apparatus comprising a tube-like element of flexible chain mesh fabric, a top supporting member for said tube-like element a discharge shell at the lower end thereof, flexible members supporting said shell, hoops secured at spaced intervals to said tube-like element and carrying guides for said flexible members. 105 110

6. Lowering apparatus comprising a tube-like element of flexible chain mesh fabric, a top supporting member for said tube-like element, a discharge shell at the lower end thereof, flexible members supporting said shell, hoops secured at spaced intervals to said tube-like element to guide and support said element when raised, and carrying guides for said flexible members, and means for operating said flexible members so as to raise and lower the discharge shell. 115 120

7. Lowering apparatus comprising a tube-like element of flexible mesh fabric adapted to receive material at the top and discharge it at the bottom, a discharge shell at the bottom of said element having an inwardly and downwardly tapered portion defining a discharge opening, a movable closure member 125 130

adapted to coact with the latter, means for moving said closure member relatively to said discharge shell, and means for raising and lowering said discharge shell.

8. Lowering apparatus comprising a tube of flexible chain mesh, flexible members adapted to collapse the tube, means for pulling in and paying out said flexible members, and means controlling the outflow of material from the tube.

In witness whereof, I have hereunto signed my name.

FRANK PARDEE.
